Primary Examiner — Holly E Thurman(57) **CLAIM**

The ornamental design for a wallet, as shown and described.

DESCRIPTION

1. Wallet
- 1.1 Cross sectional
- 1.2 Perspective
- 1.3 Perspective
- 1.4 Unfolded
- 1.5 Front
- 1.6 Left
- 1.7 Top
- 1.8 Back
- 1.9 Right
- 1.10 Bottom
- 1.11 Cross sectional
- 1.12 Cross sectional
- 1.13 Cross sectional

The broken lines do not form part of the claimed design; the dotted-dashed lines indicate the boundary between the claimed area and the unclaimed area; reproductions 1.2 and 1.3 show the inner case of the product indicated in solid lines, including the unclaimed area; the broken lines on the surface of the inner case of the product shown in reproductions 1.1 to 1.4 are stitches; reproduction 1.2 is a perspective view indicating the state in which the front panel of the outer case is folded; reproduction 1.1 indicates the state in which the front panel of the outer case is removed; reproduction 1.4 is an unfolded view indicating the unfolded state of the inner case; reproduction 1.11 is a cross-sectional view cut vertically at the left end portion of the product; reproduction 1.12 is a cross-sectional view cut horizontally at the top end portion of the product; reproduction 1.13 is a cross-sectional view cut horizontally at the bottom end portion of the product.
